UNITED STATES PATENT OFFICE.

CHARLES A. GILBERT, OF GLENS FALLS, NEW YORK.

METHOD OF MAKING SHIRTS.

SPECIFICATION forming part of Letters Patent No. 276,532, dated April 24, 1883.

Application filed March 31, 1883. (No model.)

To all whom it may concern:

Be it known that I, CHARLES A. GILBERT, of Glens Falls, in the county of Warren and State of New York, have invented certain new and useful Improvements in the Method of Making Shirts; and I do hereby declare the following to be a full, clear, and exact description of the invention, reference being had to the accompanying drawings, making part of this specification, in which—

Figure 1 shows a plan of the placket-facing and brace, put together and ready to be applied to a shirt. Fig. 2 is a cross-section of the same on line xx of Fig. 1. Fig. 3 illustrates the manner in which the first seam is run in sewing on the facing. Fig. 4 illustrates the manner in which the completing seams are run. Fig. 5 shows the placket-facing completed.

20 The object of my invention is to provide a method for applying placket-facings and a brace to the plackets of shirts, whether in the backs or in the sleeves of the garment, whereby the garment is put together in a cheap and 25 expeditious manner.

In order that those skilled in the art may make and use my invention, I will proceed to describe the manner in which I have carried it out.

30 In the said drawings, Fig. 1, A is the wider facing-piece, which goes onto the outer lap of the placket, and B is the facing for the inside lap. The outer facing, A, is folded on the line $a a'$, and a row of stitches is run to form a finish on the outer flap, and the same row of stitches is utilized to secure the stay-piece C from b to d . The stay-piece C lies over and extends about an equal distance on each side of the meeting ends of pieces A and B, and is 35

40 stitched throughout its edges, thereby holding the facing-pieces together and forming a stay against any ripping strain at the juncture of the placket when the garment is completed. The two facings A B and stay-piece C, as one

structure, is then put on the shirt. The placket 45 is spread to its fullest extent, and the edge i K l of the structure A B C, on the reverse side, is sewed on the shirt (see Fig. 3) close to the edge of the placket-opening. The whole facing is then turned over onto the body of the 50 shirt and the piece B sewed to the body on the line $m n$, so that its turned-in edge will meet the row of stitches on the line $a a'$, and appear to be a continuous seam. The piece A is then folded on the row or seam $a a'$, and is 55 stitched, and the edge passed over to the outside of the body, where it is sewed down on the line $o p$, and at the same time the tab q is sewed down and the facing of the placket is complete. A row or two of stitching, rr , may 60 be run across the tab-piece.

In my improved method of making the shirt the stitching of strip C does not appear on the outer surface when the shirt is finished. By actual experiment I have demonstrated that I 65 can, by practicing my method as herein described, make a saving of about thirty cents per dozen on good quality of shirts, and make as durable shirts as against the same shirts made with the entire facing in one piece and 70 passing across the juncture of the placket or made with the brace or stay-piece C sewed on after the placket-facing is put on.

Having thus described my invention, what I claim as new, and desire to secure by Letters 75 Patent, is—

The method of making placket-facings for shirts, consisting essentially in placing together the ends of facing A and facing B, covering the joint with the strip C, and then securing the structure A B C as an entirety onto the edge of the placket-openings by seams through A and B, substantially as set forth.

CHARLES A. GILBERT.
